UNITED STATES PATENT OFFICE.

JAMES L. MAYS, OF DALLAS, TEXAS.

POWER-TRANSMISSION MECHANISM.

1,404,628.

Specification of Letters Patent. Patented Jan. 24, 1922.

Application filed May 11, 1920. Serial No. 290,566.

To all whom it may concern:

Be it known that I, JAMES L. MAYS, citizen of the United States, residing at Dallas, in the county of Dallas and State of Texas, have invented certain new and useful Improvements in Power-Transmission Mechanism; and I do hereby declare the following to be a full, clear, and exact description of the invention, such as will enable others skilled in the art to which it appertains to make and use the same.

This invention relates to power transmission mechanism adapted to transmit uniform motion at reduced speed from a small prime mover, and to conserve energy in so doing. It comprises an organization involving a heavy momentum device adapted to effect extremely steady and efficient transmission; and the invention consists in the general organization and details of construction more specifically described hereafter and defined in the claims.

In the drawings, Figure 1 is a plan view, partly in horizontal section, of my apparatus.

Figure 2 is a side elevation thereof, indicating a portion of a frame beam broken away.

Figure 3 is a section taken on the line 30 3—3 of Figure 1, looking in the direction of the arrows.

Figure 4 is a detailed sectional view on the line 4—4 of Figure 1.

Similar reference characters designate 35 corresponding parts throughout the several views.

In the embodiment of the invention disclosed herein, the mechanism is mounted upon a base or foundation *a*, which may be an iron casting of sufficient weight to effectively check vibration. On the base casting *a*, there are, as shown, three pairs of pedestals. The main pedestals, which project from opposite sides of the base substantially midway of its length, are designated *b*. At each end of the base are other pedestals designated *c* and *c'*, respectively. Extending longitudinally of the base casting *a* are pairs of longitudinal beams or frame bars *d* and *d'*, one pair upon each side. The outer frame bar of each pair is the frame bar *d*, and the inner one is the frame bar *d'*. The spacing between the frame bars of each pair is less than the spacing between the pairs or between the two frame bars *d'*. These beams or frame bars are tied together and properly spaced by pairs of rods or bars *e*, provided, as shown, with nuts *e'* on their extremities, or with heads and nuts, said nuts or heads being located outside of the outer frame bars *d* and serving to prevent said outer bars from separating. Between the two inner frame bars *d'*, surrounding each pair of rods *e*, are spacing sleeves *f* which space the beams or bars *d'* from each other and prevent their approach. On each pair of rods *e* between the frame bars *d* and *d'* of each pair are other spacing sleeves *g*, which space the frame bars *d* and *d'* of each pair and hold them in precise and fixed relation to each other. With this construction, when the nuts *e'* are turned up on the rods *e*, the longitudinal beams or frame bars will be held in rigid, fixed relation with each other so as to constitute a frame which is sustained on the pedestals mentioned.

As thus far described, the base *a* and the pedestals *b*, *c* and *c'* constitute the fixed part of the support for the mechanism; and the frame comprising the beams *d*—*d'* and spacings bars constitute a movable frame therefor. Associated with the fixed part, as shown, is a semicircular, arched bar *h* (of which there may be two, if desired), which may be provided with a series of holes *h'* or other catch devices, for a purpose presently to be stated. Projecting from the frame heretofore referred to, comprising the beams or bars and tie rods, are members *i*, one of which may be, as shown, formed on one of the spacing sleeves *g*. Pivoted on at least one of the projecting portions *i* is a preferably spring-pressed latch *k* having, as shown, a handle member adapted to be pressed by the thumb or fingers, and a pin *l* fitted to slide through an opening in said member *i*, and engaged in one or another of the orifices *h'* in the semicircular or arched member *h* which is mounted on or secured to the fixed frame. Projecting from one or more of the members *i* are handle members *m* which diverge or are oppositely directed, as shown, although it is obvious that any suitable form of handles may be used. The longitudinal bars, tie rods, etc., already described, constitute a movable frame which supports the operative mechanism of my power transmission mechanism, and by means of strong lateral studs *n* projecting from the beams or bars *d* the movable frame is journalled upon bearings *o* on

central standards *b*. It will be apparent, therefore, that by seizing one of the handles *m* or by hooking on to it a fall, the movable frame with all of the gearing supported thereby may be turned about its pivotal support on the central standards, and, by means of the latch and arcuate bar *h*, may be secured at any desired angle between a horizontal position and a vertical position, and 10 may be completely reversed, if desired, it being understood that the transverse tie bars and spacing sleeves, at that end of the apparatus from which the handles and latch members project, are so positioned as to rest 15 upon either pair of end standards *c* or *c'*, in accordance with the position of the mechanism. It will be seen by the drawing that the distance from the pivotal center of the frame to the right-hand end, as shown 20 in Figure 1, is less than the distance between said pivotal center at the left-hand end, as shown in said figure, whereby the short end of the frame will clear the standards at one end when the opposite end of the 25 frame is supported by the standards at the other end. When in horizontal position the cross tie members on the longer end of the frame will rest in cavities *p* in one or the other of the pairs of the standards *c* or *c'*.

30 Journalled in the pivoted frame and extending completely through the beams or frame bars *d* and *d'*; so as to provide projecting portions on at least one side of the frame, are two parallel shafts 1 and 2. The 35 shaft 1 may be considered as the prime power shaft, and may carry on its projecting end a pulley 3 or other member by means of which it may be rotated from some exterior source of power, such as a small motor. In the present instance I have shown power applied to the shaft 1 from the pulley 3 by means of a speed multiplying, planetary, beveled tooth gearing. Mounted concentrically with respect to said 40 shaft, but preferably supported on a hub projecting from some rigid part of the frame and surrounding the shaft 1 concentrically, is said pulley 3. This pulley carries a radial shaft 4 upon which are mounted two beveled pinions 5 and 6 at different radial distances from the center of the pulley, the pinion 5 being of larger diameter than the pinion 6. Between the said pinions on said 45 radial shaft is a freely rotatable, conical roller 7. The said radial shaft 4 with its gears 5 and 6 and roller 7 may be duplicated, if desired; there may, for example, be four sets spaced 90° apart, mounted within the pulley. I prefer, however, as shown, to 50 make only one complete set of pinions 5 and 6 with the intermediate roller 7, and to provide three other symmetrically spaced radial shafts 5' corresponding thereto, each of which carries a conical roller 7' only. Fixed to each frame bar or beam *d* is a 55

beveled gear 8 having a conical raceway 9, the said beveled pinion 5 engaging with the teeth of said fixed beveled gear 8, and the conical rollers 7, 7' engaging with said raceway 9. Pinned or otherwise keyed or secured to the end of the shaft 1 is a small bevel gear 10, and with the teeth of said bevel gear 10 the teeth of the pinion 6 mesh. As a result of this construction, when the pulley 3 is rotated, motion will be transmitted through the pair of beveled pinions 5 and 6 to the beveled gear 10, which is fixed to the shaft 1, and the gear 10 will rotate in the same direction as the pulley 3 at a speed increased according to the ratio of gears adopted. The conical rollers traveling upon the raceway of the fixed gear 9 provide for steady operation, and reduce friction to a minimum. I have shown the shaft 1 mounted in ball bearing 1' of a well known type in the outer frame bars or beams *d*, and passing through holes in the beams *d'*.

The shaft 1 has secured to it one or more pinions 11, preferably two, as shown in Figure 1. These pinions transmit motion from the shaft 1 to the train of gearing presently to be described, and as the mechanism is symmetrical or duplicated upon opposite sides of the longitudinal center, a description of one side will be sufficient to disclose the construction of the entire mechanism.

The second shaft 2 is supported in ball bearings 20 in the frame bars *d*. Keyed to said shaft 2 is a spur gear 21 and a beveled gear 22. Rotatably mounted about the axis of shaft 2 is a large spur gear 23. Friction between said spur gear and the shaft 2 is reduced to a minimum by means of interposed ball bearing 24. A long hub 25, rigid with the gear 23, projects laterally therefrom, embracing the shaft 2 and supported in two sets of ball bearings 26 in the bar or beam *d'*. The said ball bearings may be of any approved and known type. Secured to the inner side of each frame bar *d'*, concentric with the shaft 2 is a fixed gear 27 having a peripheral row of beveled teeth 28, and an inner raceway 28'. Between the said gear 22 and the fixed bevel gear 27, the said gear 23 is disposed. Radially journalled within the gear 23 is a beveled pinion 29, said beveled pinion 29 meshing with the beveled teeth of the gear 27, which is fixed to the frame bar *d'*, and with the beveled teeth of gear 22, which is keyed to the shaft 2 at 22'. Thus, rotation imparted to the wheel 23 will cause the shaft 2 to rotate with the gearing shown at twice the angular speed of the gear 23. It is obvious that several pinions 29 might be used, if desired, but I prefer to use one such pinion, and to have a number of radially mounted, loose, conical rollers 30 angularly 130

spaced symmetrically, the surfaces of said rollers engaging raceways 22^a and 27^a in the gears 22 and 27, respectively. By this construction it will be obvious that the gear 23 will run with absolute steadiness and will create a minimum amount of resistance.

Eccentrically mounted with respect to the shaft 2, is a heavy cylindrical body 40, having a concentric orifice 40^a through it to permit the passage of the shaft 2 and the hubs of the gears 22. A ball thrust bearing 40^b is interposed between the face of the body 40 and the rear face of the gear 22. The said body 40 is recessed concentrically on each face as at 41 so as to admit the gear 23 within the recess and permit the resulting peripheral flange to overhang said gear 23. Formed with, or on a separate annulus secured to the body 40, are inner and outer rows of gear teeth. I have shown the gear teeth formed on a separate annulus or ring 42, bolted to the body 40. The outer annular row of teeth 43 meshes with a pinion 11. The inner row of annular teeth 44 meshes with the teeth of the gear 23. By this construction it will be seen that the body 40 is supported by the internal teeth 44, engaging the teeth of the gear 23, which is eccentric with respect to said body, and the external teeth 43 engaging the teeth of the pinion 11; and that there are two main points of support at the extremities of a line between teeth on the interior gear ring 44 and gear 23, and teeth on the exterior gear ring 43 and pinion 11, and that a straight line drawn between those points of support will intersect the axis of shaft 2. Secured to the back of each gear 23 is a shroud ring 45 having an outer perimeter which rolls in contact with the outer wall 46 of the cavity 41 in the face of the body 40, thus insuring correct meshing of the teeth 44 with the teeth of the gear 23, and preventing any in and out or radial sliding motion with respect to each other.

In order to assist in holding the body 40 in correct position, I prefer to journal a pair of rollers 47 on studs 48 projecting from the beam or frame bars *d'*, so that the perimeters of the said rollers will engage an annular bearing surface 48 in the ring 42, said rollers being preferably mounted on ball bearings and arranged so as, in conjunction with the rolling surfaces between the shroud ring 45 on gear 23 and the body 40, to position said body 40 with absolute precision so that there can be no sliding or grinding of the teeth, other than is incident to their rolling contact.

The ball bearings 26 referred to as mounted in the bars *d'* take all of the weight of the gear 23, and such of the weight of the body 40 as is imparted to said gear, on the frame bars *d'*, thus substantially relieving the shaft 2 of the weight of said gear and

body, said shaft 2 carrying only the weight of the beveled gears 22 and the spur gears 21. It will be noted also that the ball bearing 20, which support the shaft 2 in the frame bars *d*, are seated in bosses formed on the exterior of said frame bars, and that said bosses are reduced and trued so as to form the studs *s* that fit snugly in bearings *o* therefor, as heretofore mentioned, on the central pedestals *b* which serve as the pivotal supports of the said movable frame carrying the gearing. The studs *s* are preferably concentric with the heavy body 40.

For the purpose of producing absolute steadiness, the motion transmitted by the gearing, thus far described, to the shaft 2, is transmitted by intermediate trains back to the shaft 1; and the relative proportions or gear ratios of the transmitting gearing by which motion is transmitted back to the prime shaft 1 must obviously be made such that the final gear on the shaft 1 in this return train will be driven thereby at precisely the same angular speed as that at which the shaft 1 is initially driven. This return train will now be described.

Between the prime shaft 1 and second shaft 2, and parallel therewith, extending between each pair of beams or frame bars *d* and *d'*, is preferably a stud shaft 51 carrying an idler 52. The said idler 52 meshes with the gear 21 and with a gear 53 which is mounted on a stud shaft 54 parallel with the stud shaft 51 and extending between beams *d* and *d'*. Mounted concentrically with respect to said last named stud, is a fixed beveled gear 55 shown as bolted to a beam *d*. This beveled gear 55 is constructed similarly to the corresponding fixed gears previously described, having an external annular row of beveled gear teeth, and within that a conical raceway. Mounted loosely with respect to and concentric with said stud 54 is a beveled gear 56 of the same size as said beveled gear 55, and similarly constructed. The hub of the said spur gear 53 is mounted on ball bearings encircling said stud 54, and so also is the described beveled gear 56 which is loose upon said stud. The described spur gear 53 is mounted between the fixed gear 55 secured to the frame *d* and the said loose beveled gear 56. The said spur gear 53 carries a radially mounted, beveled pinion 57, which meshes with the beveled teeth of both the fixed gear and the relatively rotary gear 120 concentric therewith. As in other gear sets described, there may be a plurality of such beveled pinions, but I prefer to space symmetrically within said spur gear a plurality of conical rollers 58 adapted to engage raceways. It will be seen that the unit gear set just described, mounted on the said stud 54, constitutes a planetary gear set that accomplishes a reduction of speed as applied to the said loose beveled gear 56. Integral with or

secured to said loose beveled gear is an external gear ring or series of spur gear teeth 59. Mounted concentrically upon the shaft 1 is a spur gear 60, carrying preferably a plurality of beveled pinions 61, radially mounted therein. Fixed to a frame bar d' , concentric with the shaft 1, is a beveled gear 62, with which said beveled pinions 61 mesh. Keyed or otherwise secured to the shaft 1, so 10 as to rotate therewith, is a beveled gear 63. Between the said gear 62 fixed to the frame bar d' and the said gear 63 fixed to the shaft 1, the said spur gear 60 is mounted to rotate. The teeth of the spur gear 60 are in mesh 15 with the teeth of the spur ring 59 on the said beveled gear 62, and as the said gear 62 rotates, it rotates the spur gear 60, and motion will thereby be transmitted to the beveled gear 63, and therethrough to the shaft 1, the 20 ratios of the several gears between the gear ring 44 and the gear 63 being such that the said gear 63 has imparted to it by the reverse train precisely the angular speed that was imparted to the shaft 1 by the initial 25 driving motion of the pulley 3. It will thus be seen that there is, as it were, a closed mechanical circuit beginning with the shaft 1, and therefrom transmitted to the shaft 2, and back again to said shaft 1, so that the 30 said gearing holds the said two main shafts in exact responsive speed relations.

It will be seen that this mechanism as a whole may be so manipulated as to place it at any convenient angle of operation, and 35 that when erected into the perpendicular position, all weight of the heavy body 40 tending to shear the teeth, is removed from the gear teeth, and that the heavy body 40 will then be suspended substantially by the rollers 47 sustained on strong studs projecting from the frame bars d' . Assuming that the apparatus is to be driven by a belt, the belt may be tightened by shifting the position of the frame. It may be adapted to confined 45 spaces by reason of the changes of position of which it is susceptible.

Having described my invention in the best form now known to me, what I claim and desire to secure by Letters Patent of 50 the United States is:

1. In power transmitting mechanism, a frame, a bevel gear fixed thereto having on one face an annular row of bevel teeth, a smaller bevel gear coaxial with said fixed 55 gear and having a row of bevel teeth facing the said fixed gear, a wheel journaled between said bevel gears coaxial with respect to them, a radial shaft journaled in said wheel, a bevel pinion fixed to the outer end of said shaft and arranged to engage the bevel teeth of the larger fixed gear, a bevel pinion fixed to the inner end of said radial shaft and engaging the smaller and rotatable bevel gear.

2. In power transmitting mechanism, a

frame, a bevel gear fixed thereto having on one face an annular row of bevel teeth and a raceway concentric with and of a different diameter than the annular row of teeth, a second bevel gear coaxial with said fixed gear and having a row of bevel teeth facing said fixed gear, a wheel journaled between said bevel gears coaxial with respect to them, a radial shaft journaled in said wheel, a bevel pinion fixed to the outer end of said shaft and arranged to engage the bevel teeth of the fixed gear, a bevel pinion fixed to the inner end of said radial shaft and engaging the rotatable bevel gear, rollers radially pivoted in said wheel, and arranged to bear upon said raceway.

3. In power transmitting mechanism, a frame, a bevel gear fixed thereto, a rotatable bevel gear of different pitch diameter coaxial with said fixed gear and facing it, a wheel mounted between said gears coaxial therewith, a radial shaft journaled in said wheel, two bevel pinions thereon, one of which engages the teeth of the fixed bevel gear and the other the teeth of the rotatable bevel gear, a raceway on the face of the fixed gear, and a roller radially pivoted on the said wheel and bearing upon said raceway, said roller being radially spaced from the center so as to describe a path between the paths described by said bevel pinions.

4. In power transmitting mechanism, a frame, a prime shaft and a second shaft, parallel with each other, journaled in said frame, a pinion fixed to the prime shaft, a gear having external teeth concentric with the second shaft and adapted to drive it, a symmetrical heavy cylindrical body, disposed eccentrically with respect to the axis 100 of said second shaft, said cylindrical body having an external annular row of gear teeth adapted to mesh with said pinion fixed to the prime shaft, and an internal annular row of gear teeth adapted to mesh 105 with said gear concentric with the second shaft.

5. In power transmitting mechanism, a frame, a prime shaft and a second shaft journaled in said frame parallel with the prime shaft, a pinion fixed to the prime shaft, an externally toothed gear mounted concentrically with respect to said second shaft and means whereby rotation of the gear will drive said second shaft, a symmetrical heavy cylindrical body disposed eccentrically with respect to said second shaft and surrounding it, said cylindrical body having an external annular row of teeth adapted to mesh with the pinion fixed to the prime shaft, an internal annular row of teeth adapted to mesh with said gear concentric with said second shaft and being sustained by the teeth of said pinion on said prime shaft 130

and the externally toothed gear concentric with said second shaft and means for preventing said cylindrical body from moving laterally out of engagement with said pinion and externally toothed gear.

6. In power transmitting mechanism, a frame, a prime shaft and a second shaft, parallel with each other, journaled in said frame, a pinion fixed to the prime shaft, a gear having external teeth concentric with said second shaft and adapted to drive it, a symmetrical heavy cylindrical body disposed eccentrically with respect to the axis of said second shaft, said cylindrical body having an external annular row of gear teeth adapted to mesh with said pinion fixed to the prime shaft, and an internal annular row of gear teeth adapted to mesh with said gear concentric with the second shaft, and shrouds on said eccentrically disposed body and on said gear concentric with said second shaft said shrouds providing rolling surfaces adapted to engage in the pitch circumferences of the internal gear and said gear concentric with the second shaft.

7. In power transmitting mechanism, a frame, a prime shaft and a second shaft mounted in said frame parallel with each other, a pinion fixed to the prime shaft, a gear having external teeth concentric with said second shaft and adapted to drive it, a symmetrical heavy cylindrical body disposed eccentrically with respect to the axis of said second shaft, said cylindrical body having an external annular row of gear teeth adapted to mesh with said pinions fixed to the prime shaft, and an internal annular row of gear teeth adapted to mesh with said gear concentric with said second shaft, shrouds on said eccentrically disposed body and on said gear concentric with the second shaft said shrouds providing rolling surfaces in the pitch circumferences of said internal gear and said gear concentric with the second shaft, and rollers journaled in the frame and bearing against the internal circumferential wall of the cylindrical body at points diametrically opposite to the points of pressure of the gear shrouds to maintain said cylindrical body in accurate adjustment.

8. In power transmission mechanism, a frame, an externally toothed gear wheel having a hub bearing in said frame, a shaft passing loosely through said hub and journaled in the frame, an internally toothed gear eccentric to said shaft engaging said externally toothed gear, and means whereby said externally toothed gear is connected to said shaft to rotate it.

9. In power transmitting mechanism, a frame, an externally toothed gear wheel having a hub bearing in said frame, a shaft passing loosely through said hub and jour-

nalled in the frame, an internally toothed gear eccentric to said shaft engaging said externally toothed gear, a bevel gear secured to said shaft, and a bevel gear concentric therewith secured to the frame, a bevel pinion radially journaled in said externally toothed gear, and meshing with the teeth of said bevel gears, and a wheel fixed to said shaft adapted to transmit motion therefrom.

10. In power transmission mechanism, a frame, a prime shaft, an externally toothed gear rotatably mounted on an axis parallel with and substantially in the same horizontal plane as said prime shaft, and a first gear train for driving said externally toothed gear comprising a pinion fixed to said prime shaft, a heavy cylindrical body disposed eccentrically with respect to the axis of said externally toothed gear, said cylindrical body having an external row of teeth meshing with said pinion fixed to the prime shaft, and an internal annular row of teeth meshing with said externally toothed gear, and a second transmission train between said externally toothed gear and the prime shaft so proportioned as to transmit motion at precisely the same ratio as said first train.

11. In power transmission mechanism, a frame pivoted on a horizontal axis, means whereby said frame may be adjusted about said axis, a prime shaft journaled horizontally in said frame, a pinion fixed to said prime shaft, an externally toothed gear pivoted to said frame on an axis parallel with the prime shaft, a heavy cylindrical body mounted eccentrically with respect to said externally toothed gear, said cylindrical body having an external row of gear teeth meshing with said pinion and an internal row of teeth meshing with said externally toothed gear, said body being sustained by said pinion and said externally toothed gear, means to prevent radial sliding movement of said body with respect to said gear and pinion, and a second transmission train between said prime shaft and said externally toothed gear.

12. In power transmission mechanism, a frame comprising two pairs of parallel spaced beams, a prime shaft and a second shaft parallel thereto, journaled transversely in said beams, central driving connections between said shafts comprising a pinion fixed to said prime shaft and an external gear concentric with said second shaft between said two pairs of beams, driving connections between said external gear and said second shaft, a heavy cylindrical body mounted eccentrically with respect to said external gear, having an external driving connection with said pinion and an internal driving connection with said external gear, said body being disposed between said pairs of beams, and other driving trains

6
similar to each other disposed between the beams of each pair, and adapted to transmit motion between the prime shaft and the second shaft at precisely the same ratio as the 5 said train disposed between the two pairs of beams.

13. In a power transmission mechanism, a support, an angularly adjustable frame provided with aligned hubs having a horizontal 10 axis journaled in said support, a prime shaft journaled in said adjustable frame, a pinion fixed to said prime shaft, a shaft journalled on an axis eccentric to said hubs and parallel with said prime shaft, an externally 15 toothed gear adapted to rotate said shaft that is eccentric with said hubs, a heavy

cylindrical body coaxial with said hubs and surrounding said eccentric shaft, said heavy cylindrical body having an annular row of external gear teeth and an annular row of 20 internal gear teeth, the external row of gear teeth meshing with the pinion on the prime shaft, and the internal row meshing with the teeth of said externally toothed gear, and a second train between said prime shaft 25 and said shaft eccentric to the hubs, said second train being adapted to transmit motion between said shaft at the same ratio as said first described train.

In testimony whereof I affix my signature. 30

JAMES L. MAYS.
